PRECISION WELDING KIT

Lloyd A. Douglas, 5020 Whistler Drive,
Fort Worth, Tex. 76133

Filed Oct. 3, 1972, Ser. No. 294,634

Term of patent 14 years

Int. Cl. D8—05

U.S. Cl. D8—30

Fig. 3

FIG. 1 is an oblique perspective view showing the front, top and end of the precision welding kit of my design,

FIG. 2 is an end elevational view of the precision welding kit of FIG. 1,

FIG. 3 is an oblique perspective view of the precision welding kit of FIG. 1 showing the back and other side and end thereof.

The fragmented disclosure of hose elements is indicative of indeterminate length and the broken line disclosure of a carrying tray is for illustrative purposes only.

I claim:

The ornamental design for a precision welding kit, as shown and described.
